UNITED STATES PATENT OFFICE.

JOSEPH CARLISLE, OF KANSAS CITY, MISSOURI, ASSIGNOR, BY MESNE ASSIGNMENTS, OF ONE-SIXTEENTH TO CLAUDE P. UTTER AND FIFTEEN-SIXTEENTHS TO ELLA M. SCOTT, BOTH OF KANSAS CITY, MISSOURI.

OIL BURNER.

Application filed March 11, 1925. Serial No. 14,643.

This invention relates to liquid fuel burners and particularly to the well known oil burner of the overlying retort type which is so commonly used at the present time, 5 and the primary object of this invention is the provision of an oil burner which will provide points of invention to overcome the many deficiencies of the burner now on the market.

10 One of the objects of this invention is the provision of an oil burner which does not carbonize.

Another object of this invention is the provision of an oil burner which embodies 15 the proper size of pipe used in the coil thereof with the proper relative size of jet.

A further object of the present invention is to provide an oil burner which has a mixing chamber of proper shape to cause the 20 generated gas to mix with the proper quantity of air and at the proper time to produce a flame which burns with the highest degree of efficiency possible from the quality of oil used.

25 An even further object of the present invention is the provision of a novelly constructed coil which has a series of abrupt turns therein for the purpose of slowing down the flow of oil and causing the same 30 to properly convert into a more efficient combustible gas.

A still further object of this invention is to provide a counter-sunk jet which is provided with roughened inner walls for the 35 purpose of agitating the gas after it passes upwardly through the jet in the bottom thereof.

This invention further contemplates the use of a gravity coil which does not have 40 a supply of oil therein during the generating period and which consequently, shortens the period of generation to approximately two minutes. This particular construction of coil eliminates entirely the possibility of 45 carbonization, since it is during the period of generation in most oil burners that the most carbon is formed.

A further object of this invention, and 50 one of the most important features, is the provision of a proper draft for the burner. This is accomplished through the particular construction of the mixing chamber and base.

In constructing this burner, care should be

taken to use materials of proper size and 55 when the heating capacity of the burner is to be increased, all parts contained therein should be proportionately increased in size. The burner shown in the accompanying drawing has been constructed for use in the 60 ordinary kitchen or laundry stove or in small stoves which are used for cooking. In the drawing:

Figure 1 is a plan view of the oil burner showing in particular the novel and necessary shape of the coil. 65

Fig. 2 is a vertical central section through the burner taken on line II-II of Fig. 1.

Fig. 3 is a horizontal section of the burner taken on line III-III of Fig. 2 and reduced in size; and, 70

Fig. 4 is a vertical central section of the preferred form of jet which should be used with this oil burner.

Referring at this time to the particular 75 points of construction of the burner shown in the drawing, wherein similar reference characters refer to like parts throughout the several views, 5 is the base of the burner which is formed to provide a floor 6 having 80 a flange 7 extending entirely there-around and which combines with floor 6 to furnish a flash pan used when generating the burner. The base 5 is preferably formed of metal and has its ends open to provide passage 85

for air which may also pass beneath floor 6 through openings 8 formed in each of the sides of base 5. Floor 6 is provided with a pair of draft openings 9 which should be near the center of the burner and have their 90 oppositely disposed sides arcuate and concentric with a jet 10 which is carried by one end of pipe 11 supported between draft openings 9. A pair of elbows 12 and 13 connected by pipe 14, join one end of vertical 95 pipe 15 which extends upwardly from floor 6 at a point near one end. This pipe 15 continues to form coil 16 as shown in Fig. 1 and is again turned down to form portion 100 17 which passes through floor 6 at the opposite end thereof and there joins through the intermediacy of elbow 18, the supply pipe 19 which leads from the tank of fuel oil not here shown.

The coil 16 must be formed with a series 105 of abrupt turns or "breaks" 20 which slow down the flow of oil therethrough and gives it the proper time to crack and become a gas

before passing through passages 15, 13, 14, 12, 11 and jet 10. The supply pipe 19 should be approximately $\frac{3}{16}$ inch pipe and a needle valve, not here shown, should be used to govern the flow of oil. The pipe constituting the coil 16 and portions 15 and 17, should be approximately 26 inches in length from the point where it passes through floor 6 and should also be quarter inch stock. These relative sizes must be maintained to keep too much oil from entering the coils and cooling the same which causes improper combustion. These relative sizes also preclude what is known as the "bucking" in the flame from an over supply of fuel being forced into the generating coil 16.

To properly carry out the conception of this invention, a mixing chamber 21 must be provided to be positioned above draft openings 9 and around jet 10 which has its base joining the arcuate sides of draft openings 9 and continuing therewith to a point where the arcuate sides of the openings end. At that point the mixing chamber forms draft arches 22 which bridge the space between said draft openings. These draft arches are two in number and are positioned diametrically opposite each other as shown in Fig 1, to form, together with openings 9, a complete draft inlet for air which is to be mixed with the gas issuing from jet 10. Mixing chamber 21 is tapered inwardly toward the top as shown in Fig. 2 and the same tends to force the air drawn in through openings 9 and 22 into the gas. As is shown, the jet 10 is positioned at nearly the top of the draft arch 22 which causes the air to be drawn in instead of being forced out. The tapered form of the mixing chamber not only allows air to pass upwardly around the stream of gas issuing from jet 10 but acts in the capacity of a guide to direct the upward flowing air toward the stream of hot gas to cause a thorough mixture. Obviously the air as it passes up through mixing chamber 21, is heated and does not cool the gas enough to cause the same to be converted into oil again. Combustion takes place approximately on a line with the top of mixing chamber 21 and the flame strikes flame spreader 23 which is hung by any suitable means 24 to coil 16. This flame spreader is not an important feature of the invention, but must be used to guide the flame in the proper direction and also protect, to a certain extent, the coils from coming in direct contact with the flame proper which would cause the same to over-heat.

With reference at this time to the preferred form of jet as shown in Fig. 4, the same comprises a member 25 having an enlarged passage 26 extending upwardly from its jet 10 which should be low enough to

permit the gas to reach a substantial distance above the jet before it is properly mixed with air and burned. The inner walls of opening 26 are roughened considerably to form an agitating surface for the gas. This jet will never carbonize.

Operation

In generating the oil burner, oil is allowed to flow through pipe 19 to elbow 18 and around to jet 10 through pipes 17, 16, 15, 14, 13 and 12 where it flows to the flash pan formed by floor 6 and flanges 7 through a groove 27 leading from jet 10. When the supply of oil is cut off, coil 16 will clear itself of oil through its peculiar construction and only a small amount of oil will remain in pipe 17. Oil in the flash pan is now ignited by using a wick if necessary and the coil 16 is heated in the shortest possible time due to the fact that it is entirely dry and no oil is contained therein to absorb heat. As soon as the coil 16 has been heated sufficiently, the oil is again turned into coil 16 and is converted into gas which immediately passes around to jet 10 where it mixes with air in the mixing chamber 21 and is ignited at a point just above the same as previously described. From this point on, the heat from the flame will maintain the coil 16 at a temperature high enough to form the oil passing therethrough into a combustible gas. It is notable that the amount of oil consumed by this burner is extremely low for the results obtained.

It is understood that the burner may be made in many various sizes and that the base may be modified to a different shape if desired, and it is understood that the construction of this invention is limited only by the appended claims and the prior art.

What is claimed is:

1. In a liquid fuel burner, a body formed to provide a base and a floor furnishing a flash pan, said floor having a pair of spaced apart draft openings adjacent the center thereof, said openings having their oppositely disposed sides arcuate and concentric with a jet supported there-between and carried at the end of a pipe extending upwardly from near one end of said floor to form a coil thereabove, the other end of said pipe passing through said floor near its other end to be joined to a supply pipe and a mixing chamber positioned above said draft openings and around said jet, said chamber joining and conforming to the arcuate sides of said draft openings and having upwardly extending draft arches bridging the space between said draft openings whereby an even supply of air is passed upwardly entirely around the gas issuing from said jet.

2. A liquid fuel burner comprising in

combination, a body formed to provide a base and a floor furnishing a flash pan, said floor having a pair of spaced apart draft openings adjacent the center thereof, 5 said openings having their oppositely disposed sides arcuate and concentric with a jet supported there-between and carried at the end of a pipe which extends beneath said floor and upwardly there-through from 10 near one end thereof to form a coil there-above, the other end of said pipe passing through said floor near its other end to be joined to a supply pipe, a mixing chamber positioned above said draft openings and 15 around said jet having draft arches therein, and means for directing the flame carried by said coil, the coil carried above said floor being formed substantially diamond shaped to provide a plurality of obtuse turns there- 20 in whereby the even flow of oil is interrupted for the purpose of and substantially as set forth.

3. A liquid fuel burner comprising in combination, a body formed to provide a 25 base and a floor furnishing a flash pan, said floor having a pair of spaced draft openings adjacent the center thereof, a jet supported between said openings and carried at the end of a pipe which extends beneath said 30 floor and thence upwardly from near one end thereof to form a coil there-above, the other end of said pipe passing through said floor near its other end to be joined to a supply pipe, a mixing chamber positioned 35 above said draft openings and around said jet and a flame spreader supported by the coil above said mixing chamber, said coil being provided with a plurality of abrupt turns therein and gradually becoming lower 40 as it leaves the point where oil is first introduced into said coil.

4. In a liquid fuel burner, a body formed to provide a base and a floor furnishing a flash pan, said floor having a pair of spaced apart draft openings adjacent the 45 center thereof, said openings having their oppositely disposed sides arcuate and concentric with a jet supported there-between, a flange extending around said opening and spaced apart from the same, a jet supported 50 between said openings and a mixing chamber positioned above said draft openings and maintained in said position by the flange there-around, a coil over-lying said base having a plurality of oppositely disposed abrupt turns therein and a flame deflector carried by said coil, said mixing chamber being tapered inwardly from the bottom towards the top and having a pair 55 of draft openings therein, said draft openings extending upwardly from the bottom and each having its side walls diverging from each other as the bottom is approached to form openings over-lapping the draft 60 openings in said base.

5. In a liquid fuel burner, a body formed to provide a base and a floor furnishing a flash pan, spaced apart draft openings adjacent the center of said floor, a diamond shaped coil over-lying said body, a mixing 70 chamber disposed above said draft openings and a jet member carried at the out-let end of said pipe and within said mixing chamber, said diamond shaped coil having a pair of oppositely disposed obtuse angle turns 75 therein and having its entire length gradually and progressively lowered as the point where the oil leaves the coil is approached.

In testimony whereof I hereunto affix my signature this 7th day of March, 1925.

JOSEPH CARLISLE.
